FIG. 6 is a side exploded view thereof;

FIG. 7 is a cross-sectional view of the ceiling fan part taken along line 7-7 of FIG. 3, in the first embodiment;

FIG. 8 is a perspective view of a ceiling fan part of a second embodiment;

FIG. 9 is a side view thereof; since the ceiling fan part is round and symmetrical, all side views are identical;

FIG. 10 is a top view thereof;

FIG. 11 is a bottom view thereof;

FIG. 12 is a perspective exploded view thereof;

FIG. 13 is a side exploded view thereof;

FIG. 14 is a cross-sectional view of the ceiling fan part taken along line 14-14 of FIG. 10, in the second embodiment;

FIG. 15 is a perspective view of a ceiling fan part of a third embodiment;

FIG. 16 is a side view thereof; since the ceiling fan part is round and symmetrical, all side views are identical;

FIG. 17 is a top view thereof;

FIG. 18 is a bottom view thereof;

FIG. 19 is a perspective exploded view thereof;

FIG. 20 is a side exploded view thereof;

FIG. 21 is a cross-sectional view of the ceiling fan part taken along line 21-21 of FIG. 17, in the third embodiment;

FIG. 22 is a perspective view of a ceiling fan part of a fourth embodiment;

FIG. 23 is a side view thereof; since the ceiling fan part is round and symmetrical, all side views are identical;

FIG. 24 is a top view thereof;

FIG. 25 is a bottom view thereof;

FIG. 26 is a perspective exploded view thereof;

FIG. 27 is a side exploded view thereof;

FIG. 28 is a cross-sectional view of the ceiling fan part taken along line 28-28 of FIG. 24, in the fourth embodiment;

FIG. 29 is a perspective view of a ceiling fan part of a fifth embodiment;

FIG. 30 is a side view thereof; since the ceiling fan part is round and symmetrical, all side views are identical;

FIG. 31 is a top view thereof;

FIG. 32 is a bottom view thereof;

FIG. 33 is a perspective exploded view thereof;

FIG. 34 is a side exploded view thereof;

FIG. 35 is a cross-sectional view of the ceiling fan part taken along line 35-35 of FIG. 31, in the fifth embodiment;

(Continued)

FIG. 36 is a perspective view of a ceiling fan part of a sixth embodiment;
 FIG. 37 is a side view thereof; since the ceiling fan part is round and symmetrical, all side views are identical;
 FIG. 38 is a top view thereof;
 FIG. 39 is a bottom view thereof;
 FIG. 40 is a perspective exploded view thereof;
